Attorney.

UNITED STATES PATENT OFFICE.

IRA M. CLARKE, OF PITTSBURGH, PENNSYLVANIA, ASSIGNOR TO THE NEW MARTINSVILLE GLASS MANUFACTURING COMPANY, OF NEW MARTINSVILLE, WEST VIRGINIA, A CORPORATION OF WEST VIRGINIA.

LENS.

1,315,283.

Specification of Letters Patent. Patented Sept. 9, 1919.

Application filed August 9, 1918. Serial No. 249,197.

To all whom it may concern:

Be it known that I, IRA M. CLARKE, a citizen of the United States, and resident of Pittsburgh, in the county of Allegheny and State of Pennsylvania, have invented a new and useful Improvement in Lenses; and I do hereby declare the following to be a full, clear, and exact description thereof.

My invention relates to lenses and has special reference to such lenses for use as a headlight for automobiles and other vehicles.

The object of my invention is to provide a cheap, simple and efficient form of lens which will diffuse the light when used on a vehicle, as well as one which also, when so used, will prevent glaring.

To these ends my invention consists, generally stated, in the novel arrangement, construction and combination of parts, as hereinafter more specifically set forth and described, and particularly pointed out in the claims.

To enable others skilled in the art to which my invention appertains to construct and use my improved lens, I will describe the same more fully, referring to the accompanying drawing, in which—

Figure 1 is a face view of my improved lens;

Fig. 2 is a vertical section of the same on the line 2—2 Fig. 1;

Fig. 3 is a cross-section of the same on the line 3—3 Fig. 1, looking in the direction of the arrows;

Fig. 4 is a like view taken on the line 4—4 Fig. 1, looking in the direction of the arrows; and

Fig. 5 is an edge view of the same.

Like symbols of reference herein indicate like parts in each of the figures of the drawing.

As illustrated in the drawing, my improved lens is shown at A and is formed of a single piece of clear glass, and which is capable of being made by the ordinary pressing operation in the usual manner. The lens A is of circular or disk shape in form, and with the exception of a slight annular rib 1 on the back or rear surface 2, such surface is of substantially flat form, and has the annular flange or rim 3 at its outer extremity or periphery, for securing or holding such lens in a lamp or other lighting device (not shown). Extending outwardly

from such flange or rim 3 is the front face 4, which is connected to such rim by the annular outwardly extending flange portion 5, in line with the rib 1, for forming the periphery of such face; and such face tapers inwardly, as at 5', and is provided with the concave or bulbous prism portion 6 and prism portion 7 above the same. This top prism portion 7 is formed above the horizontal center or axis of the front face 4 and connects with said face through an outwardly extending horizontal lip 7', and such portion is provided with the two faces 8, which are formed on each side of the vertical center or axis of such portion and are curved inwardly and downwardly from the periphery or flange portion 5 to such center or axis. The outer edge 9 on the concave or bulbous portion 6 is formed on tapered bevel, as at 10, from the horizontal lip 7', and by reason of the form of the inclined faces 8, such edge curves inwardly, as at 11, from said lip, while such edge slightly below such lip on such concave or bulbous portion 6 curves upwardly and outwardly to such lip and outwardly and downwardly to the bottom of the vertical center or axis of such portion from approximately the horizontal center or axis of said portion, as at 12 and 13, respectively.

In the use and operation of my improved lens A when applied to the headlight of an automobile, it will be obvious that the concave or bulbous prism portion 6 will throw the light forwardly and downwardly at a gradually increasing degree from the upper portion to the lower portion of said prism portion, while the inclined top prism faces 8 will throw the light outwardly to the right and left respectively of the driver and also downwardly, thereby giving a greater intensity of light immediately in front of the vehicle.

It will thus be seen that in the use of my improved lens there will be a great width of the light therefrom in illuminating the roadway in front of and on each side of the vehicle and also the area immediately in front of the vehicle.

Various changes in the design and construction of my improved lens may be resorted to, without departing from the spirit of the invention, or sacrificing any of its advantages.

What I claim as my invention and desire to secure by Letters Patent is:

1. A lens of the class described comprising a substantially plano-concave lower prism portion with its curved surface formed in one continuous curve outwardly and downwardly, and an upper prism portion above said lower prism portion and above the horizontal axis of the lens, said upper prism portion being formed of two prisms curved inwardly toward the vertical axis of the lens.
2. A lens of the class described comprising upper and lower prism portions, the upper portion being formed of two prisms curved

downwardly and inwardly toward the vertical axis of the lens, and the lower portion consisting of a single substantially plano-concave prism, the angularity of the curved surface to the plane surface of said prism uniformly increasing downwardly and laterally.

In testimony whereof I, the said IRA M. CLARKE, have hereunto set my hand.

IRA M. CLARKE.
